FIREARM

Filed Oct. 4, 1928

UNITED STATES PATENT OFFICE

CRAWFORD C. LOOMIS, OF ILLION, NEW YORK, ASSIGNOR TO REMINGTON ARMS COMPANY, INC., A CORPORATION OF DELAWARE

FIREARM

Application filed October 4, 1928. Serial No. 310,305.

The present improvements are particularly applicable to rifles of the type commonly called "single shot rifles" in which a fired shell is ejected and a fresh cartridge manually inserted for each operation. On account of the manual operation of this type of gun, it is desirable to provide certain safeguards against incomplete and improper manipulations which are automatically prevented in guns of the "repeating" or "self loading" type.

It is an object of the present invention to provide a gun which will require a certain sequence of operation for ejecting and re-loading, which precludes the possibility of premature firing or accidental discharge when the breech is not properly locked.

A further object of the invention is to provide an improved firing spring and pilots for this spring which prevent abnormal displacement or malfunctioning. A further object of the invention is to utilize a part of the breech block as an abutment for the firing spring and in this manner to cause the firing spring to control the movement of the breech block as well as the hammer. A further object of the invention is to provide an improved means for retaining the fire control mechanism in place when the barrel is removed.

With these and other objects in view, the invention consists in the novel combination and arrangements of parts, a representative embodiment of which is shown in the illustrative drawings and will be hereinafter described.

In the drawings:

Fig. 1 is a fragmentary side elevation of the gun to which the present invention may be applied.

Fig. 2 is a fragmentary longitudinal sectional elevation showing the mechanism in loading position.

Fig. 3 is a longitudinal sectional elevation showing the action closed, and including the take down mechanism.

Fig. 4 is a cross sectional view taken on line 4-4 of Fig. 3.

Fig. 5 is a plan view of the receiver and fire control mechanism, the barrel being removed.

In the drawings the numeral 10 indicates the receiver, to the rear portion of which a stock 11 is secured by suitable means such as a tang screw 121. A barrel 12 is likewise secured to the receiver in a manner to be hereinafter described. The receiver 10 contains the breech block 14, the hammer 15 and the trigger 16, and carries the trigger guard 17.

The breech block is pivoted at 18 and extends rearwardly and upwardly to form the chamber closing head 19, from which a knurled finger piece 20 extends laterally as shown in Fig. 5. A firing pin 21 extends through the head 19 and is recessed to receive the shank 201 of the finger piece 20, which thus acts as a retaining pin.

The hammer is provided with two notches 25 and 26 respectively, adapted to be engaged by the nose 27 of the trigger. The notch 25, which holds the hammer in intermediate or half cocked position is adapted to engage the trigger nose in such a way as to prevent release of the hammer from this position. It is necessary that the hammer be fully cocked before it can be released for firing movement. The hammer is also provided with a shoulder 23 which is substantially concentric with the pivot 22 and with a second shoulder 24, both of which are adapted for cooperation with the heel 231 of the breech block. When the gun is closed the shoulder 23 engaging the heel 231 serves as a breech lock. A thrust upon the breech block tending to rotate it about its pivot 18 is transmitted through its engaging surfaces in a line passing through the pivot 22. Thus movement of the hammer to breech releasing position is prevented.

When the action is in half cocked position as shown in Fig. 2, the heel 231 engages the lower shoulder 24 of the hammer stopping the downward movement of the breech block. When the hammer is drawn to fully cocked position the heel 24 moves upwardly carrying the breech block into a position in which it obstructs the insertion or removal of a cartridge or shell from the chamber.

The firing movement of the hammer is effected by means of a coil spring 28 carried upon spring pilots 29 and 30 which engage respectively with suitable recesses in the

breech block and the hammer. The pilot 29 comprises a tubular portion adapted to telescopically receive the free end of pilot 30 and the spring 28 is compressed between shoulders upon the two pilots. Correct alignment and free movement of the spring is thus insured. Moreover, the firing spring serves to yieldingly retain the breech block in chamber closing position after it is moved upward-

10 ly toward this position. As the breech is opened the end of pilot 29 moves downwardly across a line between the pivot 18 and the end of pilot 30 after which the spring urges the breech block downwardly. A single spring is

15 thus made to function as a firing spring and the means for yieldingly retaining the breech block in either closed or open position.

Pivoted in the forward end of the breech block member at 31 is an extractor 32 within 20 a recess in the breech block and partly in the barrel. The extractor comprises an upturned forked end 33 for engagement with the shell rim and a forwardly extending toe 34 overlying a shoulder 35 on the receiver. 25 The extractor is urged counter clockwise by spring 36 occupying a recess in the breech block and engaging the lower edge of the extractor.

The invention contemplates both improved 30 means for securing the forearm to the barrel and an improved take down device. The forearm 40 is held to the barrel by means of a screw 41 which enters a threaded opening in the barrel. A countersunk opening in the 35 forearm receives the screw and a metal cup 42 which contains the screw head and protects the wood of the forearm against wear and abrasion by the screw. The barrel is secured to the receiver by a take down device constructed as follows:

A plug 45 is received in a threaded recess in the barrel and is tightly fitted therein. The plug comprises an extending shank 46 which is counterbored and threaded to receive the 45 enlarged and threaded end of the take down screw 47. The enlarged and threaded end of screw 47 occupies a countersink in the receiver metal and can only be removed by turning through the threads of the screw 50 shank receiving opening 48. The screw 47 is manipulated by means of a knurled head 49.

The operation of the mechanism is as follows:

When it is desired to load the gun the hammer must be moved to half cocked position as shown in Fig. 2, in which position it is locked against firing movement. If the hammer is moved to fully cocked position the breech block is elevated by the engagement of heel 231 with shoulder 24 and prevents the insertion of a cartridge. A cartridge having been placed in the chamber with the hammer in half cocked position the gun may be carried if desired, without closing the breech 65 and with the hammer either half cocked or

fully cocked, the cartridge being held in the chamber by the extractor 29, which is urged into frictional engagement with the cartridge by its spring 36. The hammer may be cocked but if an attempt is made to fire the gun without the breech being closed, the forward face 152 of the hammer merely engages the rear face of the breech block preventing any part of the hammer coming in contact with the firing pin. The breech being properly closed is held in closed position by the pressure of the firing spring 28, the hammer may then be released by pressure on the trigger and as it falls the shoulder 23 engaging the heel 231 effectively locks the breech before the hammer strikes the firing pin. The gun being fired the hammer must again be brought to half cocked position in order to permit the opening of the breech by downward pressure on the finger piece 20. As the breech is 85 opened the extractor is moved rearwardly thereby withdrawing the fired shell to the position shown in Fig. 2 from which it can be manually removed. The toe 34 of the extractor overlies the shoulder 35 in all positions of the mechanism and when the gun is taken down by withdrawing the take down screw from plug 45 and removing the barrel and forearm this engagement of the extractor toe with the receiver holds not only the extractor but also the breech block and the firing spring in proper position. Accidental displacement and loss of any part of the fire control mechanism when the gun is taken down is thus prevented.

While the form of mechanism herein described is admirably adapted to fulfill the object primarily stated, it is to be understood that it is not intended to confine the invention to one embodiment herein shown, since it may be embodied in various forms, all coming within the scope of the appended claims.

What is claimed is:

1. In a firearm comprising a breech block and a firing hammer, a common spring controlling said breech block and said hammer and a pair of telescopically engaging pilots for said spring, one of said pilots being in abutment with said hammer and the other of said pilots in abutment with said breech block.

2. In a firearm comprising a receiver, a barrel demountably attached to said receiver, a breech block in said receiver and an extractor device pivoted to said breech block, means associated with said extractor device for preventing abnormal displacement of said extractor and said breech block when the barrel is removed from the receiver.

3. In a firearm comprising a receiver, a barrel demountably attached to said receiver, a fire control mechanism comprising a breech block in said receiver, an extractor pivoted to said breech block, a firing hammer, a spring compressed between said breech block and

- said firing hammer, means for preventing abnormal displacement of said fire control mechanism when said barrel is removed comprising a device associated with said extract 5 tor and adapted to engage a wall of said receiver.
4. In a gun of the class described the combination with a barrel and a receiver frame, of a pivoted breech block in said receiver, 10 manipulating means extending from said breech block, a firing pin in said breech block and means whereby said pin is retained in said block by the mounting of said manipulative means.
- 15 5. In an extracting mechanism for firearms a receiver frame, a firing chamber, a pivoted breech block normally closing said chamber, a spring pressed extractor member pivoted on said block and adapted to register with said 20 chamber, means whereby the rocking movement of said block will impart an extracting movement to said extractor and other means whereby the rocking movement of the extractor will be guided by the said receiver 25 frame.
6. In a firearm comprising a pivoted breech block and a firing hammer, a common spring controlling said breech block and said hammer and a pair of telescopically engaging 30 pilots for said spring, one of said pilots being in abutment with said hammer and the other of said pilots in abutment with said breech block, the line of thrust of said spring being shiftable from one side of the breech block 35 pivot to the other as said breech block is moved from opened to closed position or vice versa.
7. In an extracting mechanism for firearms, a barrel, a receiver frame, a breech block 40 pivoted in said frame, an extractor member pivoted on said breech block and arranged for sliding engagement with said barrel.
8. In an extracting mechanism for firearms, a barrel having a firing chamber, a receiver frame, an extractor member pivoted on said breech block and having a free end registering with said chamber, means to guide said member whereby a rocking movement of said breech block will impart to the free end of said member a movement substantially 45 in translation.
9. In an extracting mechanism for firearms, a barrel having a firing chamber, a receiver frame, a breech block pivoted in said frame, an extractor member pivoted on said breech block and adapted to register with said chamber, and resilient means interposed between said member and said breech block.
- 50 10. In an extracting mechanism for firearms, a barrel having a firing chamber, a receiver frame, a breech block pivoted in said frame, an extractor member pivoted intermediate its ends on said breech block, one end 55 of said member being adapted to register with 60 said chamber and the other end engaging a portion of the receiver wall, and resilient means interposed between said breech block and said member.
